LUMINAIRE

George P. Wakefield and Harvey H. Vick, Vermilion, Ohio, assignors, by mesne assignments, to Wakefield Corporation, Detroit, Mich., a corporation of Michigan
Filed Nov. 16, 1960, Ser. No. 69,661
7 Claims. (Cl. 240—51.11)

The present invention relates generally as indicated to a luminaire and, more particularly, to improvements in the refractor therefor and in the fixture body, as well.

It is a principal object of this invention to provide a luminaire having a transparent refractor that re-directs a considerable portion of the light flux upwardly at about a 45° angle, whereby, when the luminaires are mounted on stems beneath a room ceiling, the brightness difference between the ceiling and the luminaires is substantially reduced. Such re-direction of the light flux upwardly also tends to produce an even ceiling brightness between rows of on-ceiling mounted luminaries. Moreover, such re-direction aids in brightness control at the sides of the luminaires and increases the overall efficiency by increasing the areas of the light transmitting media around the light sources.

It is another object of this invention to provide a luminaire in which the refractor thereof has narrow horizontal light transmitting bands parallel to the adjoining channel of the luminaire body so as to transmit direct upward flux to the ceiling in case single rows of luminaires are used, otherwise these areas on the ceiling are blacked out when such light-transmitting bands are omitted.

It is another object of this invention to provide a luminaire in which the refractor thereof has smooth exterior sides to facilitate cleaning, and the interior sides are prismatic to re-direct light downwardly and to refract light upwardly.

It is still another object of this invention to provide a luminaire in which the bottom of the refractor thereof has a simplified form of light control formation composed of crisscross rows of cones effective to provide for even brightness control.

It is still another object of this invention to provide a luminaire in which the refractor is partially luminous at its ends to transmit light endwise of the luminaire, whereby, in the case of continuous runs wherein two or more luminaires are mounted in end to end relation, the joints will be luminous, and unnoticeable.

It is still another object of this invention to provide a luminaire of the character indicated which has a built-in channel which is exteriorly shaped for accommodating longitudinally adjustable clamp-on fittings for ceiling or stem mounting, and which is interiorly shaped for detachable engagement by a snap-in cover that serves as a reflector between the lamps and as a cover for the ballast mounted in the channel and that forms a wireway with the channel.

It is yet another object of this invention to provide a simple form of luminaire and refractor therefor which is inexpensive to manufacture and with which superior light control is achieved.

It is still another object of this invention to provide a luminaire of the character indicated which has a novel form of lamp holder support structure removably attached at each end of the luminaire body.

It is still another object of this invention to provide a luminaire in which the refractor thereof is yieldably held in place against vibration and air currents and is mounted for downward swinging movement (and removal, if desired) from either of its upper edges to facilitate re-lamping and other service.

Other objects and advantages of the present invention

2

will become apparent as the following description proceeds.

To the accomplishment of the foregoing and related ends, the invention, then, comprises the features herein-after fully described and particularly pointed out in the claims, the following description and the annexed drawings setting forth in detail certain illustrative embodiments of the invention, these being indicative, however, of a few of the various ways in which the principle of the invention may be employed.

In said annexed drawings:

FIG. 1 is a perspective view of a preferred embodiment of this invention and being broken away in part to clearly show the internal construction of the luminaire;

15 FIG. 2 is a fragmentary longitudinal cross-section view taken substantially along the line 2—2, FIG. 3 from about the middle of the luminaire toward one end to show how the ballast is mounted and enclosed in the channel, to show one of the stabilizing protuberances for on-ceiling 20 mounting, and to show one of the wire lead retainers;

25 FIG. 3 is a transverse cross-section view of the luminaire herein taken substantially along the line 3—3, FIG. 2 and showing (in dotted lines) how the refractor is swung down about either one of its top edges for re-lamping or other purpose;

FIG. 4 is a fragmentary longitudinal section view on enlarged scale taken through one end of the luminaire substantially along the line 4—4, FIG. 1;

30 FIG. 5 is a fragmentary longitudinal cross-section view showing a luminaire to accommodate refractors in end to end relation;

35 FIG. 6 is a much enlarged fragmentary cross-section view illustrating the conical formation at the bottom of the refractor, such section having been taken substantially along the line 6—6, FIG. 4;

FIG. 7 is a bottom plan view as viewed upwardly in FIG. 6;

40 FIG. 8 is an enlarged cross-section view of a portion of the refractor herein showing how the principal light rays are reflected and refracted; and

FIGS. 9 and 10 are typical candlepower distribution and brightness graphs respectively of the luminaire embodying the present invention.

45 Referring now in detail to the drawings, and first more especially to FIG. 1, the luminaire 1 herein comprises a body or channel and reflector assembly 2 with end caps 3 at each end against which lamp holders 4 in supports 5 (see FIG. 4) are positioned for engagement with the terminals of fluorescent or like lamps 6; and a refractor 50 7 supported by said assembly 2 and having opposite downwardly divergent sides 8 which are interiorly grooved to form reflecting and refracting prisms, and a bottom brightness control surface 9 composed of crisscross rows of cones 10 (see FIGS. 6 and 7) intersecting one another to provide square bases when viewed upwardly from beneath the luminaire 1.

55 The refractor 7 is preferably injection molded of crystal acrylic plastic to provide transparent sides 8 and bottom 9 and to provide frosted or translucent ends 11 with the translucent portion extending to the bottom tangent lines of the refractor as denoted, for example, by the reference numeral 12 in FIG. 4. Such plastic (methyl methacrylate) has excellent molding properties, and other properties such as tensile, flexural, and impact strengths, low water absorption, good sunlight resistance, and high transparency (>92% light transmission) to make it a superior material for the manufacture of instant refractor 7. This material has a refractive index of 1.49.

60 70 The reflector and channel assembly 2 includes a body member 14 as of formed sheet metal having a central downwardly open channel 15 of which the upper side

portions 16 converge downwardly to receive conventional clamp-on type fittings 17 (see FIG. 3). The body member 14 has upwardly diverging reflecting surfaces 18, a pair of upwardly opening grooves 19 in either of which the corresponding edge of the refractor 7 is received for swinging movement as later explained in detail, and a pair of horizontally disposed refractor support flanges 20 which are downwardly offset so as to provide shoulders 21 for centering the refractor 7.

As shown, the upper side portions 16 of the channel 15 form catches to yieldably receive the longitudinal ribs 23 along the upper edges of the snap-in cover member 24 which has a V-shaped bottom portion to provide continuations of the surfaces 18 of the body member 14. Thus, with the cover member 24 snapped into place in channel 15 there is formed therebetween a closed wire way and, in addition, the cover member 24 is formed with longitudinally extending bulges 25 at about the mid-portion of the length thereof to accommodate the lighting fixture ballast 26 which may be held in place as by a tongue 27 struck down from the web of the channel 15 to receive the flange at one end of the ballast (see FIG. 2), and by a screw and nut assembly 28 extending through the flange at the other end of the ballast.

The body member 14 may be formed with stabilizing protuberances 29 near the ends for engagement with the room ceiling when the luminaire is attached directly to the ceiling.

Extending crosswise of the channel 15 beyond the ends of ballast 26 are wire lead retainers 30 (see FIGS. 2 and 3).

As best shown in FIGS. 3 and 4, at each end of the channel and reflector assembly 2 is an end plate 3 which has an inturned top flange 31 attached as by rivets 32.

Inside each end plate 3 is a lamp holder support 5 which has a bottom outwardly extending flange 34 to which a leaf spring member 35 is riveted as shown, and intermediate side lugs 36 which are bent outwardly and threaded, whereby screws 37 may be employed to secure the respective lamp holders 4 in place.

Each lamp holder support 5 has a top inwardly extending flange 38 which is yieldably held by a hook or catch member 39 struck out from the body member 14. Each end plate 3 and lamp holder support 5 may be provided with the usual knock-outs (not shown) for wires, but to impart decorative influence to the luminaire, there may be affixed on each end plate 3 a suitable knock-out cover 40 as of aluminum foil or the like. Also, for additional aesthetic purpose each end plate 3 may be formed with a small opening 41 therethrough and on the rear side, there may be attached a transparent colored pressure sensitive disk 42 which may be of any desired color.

Insofar as the refractor 7 is concerned, and as previously mentioned, it has opposite downwardly diverging sides 8, the upper ends of which terminate in horizontal inturned flanges 45 which are adapted to rest on the horizontal flanges 20 of the body member 14, and by reason of the step 21, the refractor 7 is thereby centered with respect to the channel and reflector assembly 2. The open ends of the refractor 7 are of less height and width than the end plates 3 and the edges 46 are engaged by the leaf springs 35 to yieldably hold the flanges 45 and 20 in engagement.

When it is desired to service the luminaire 1, all that one has to do is to lift either side of the refractor 7 to position the flange 45 above the corresponding step 21 and to shove the thus-lifted side of the refractor toward the reflector assembly 2, whereupon the lifted flange 45 is disposed in the groove 19 on that side of the luminaire and retained therein by the top flanges 31 of the end plates 3 which overlie portions of the grooves 19. Accordingly, when the opposite side of the refractor 7 is allowed to drop down, its other flange 45 will clear the other flange 20 so that the refractor 7 will swing to the dotted line position shown in FIG. 3 thus, providing ready access to the right-hand lamp 6. Similarly, if the left-hand lamp 6 is

to be replaced, the right flange 45 of the refractor 7 will be positioned in the right groove 19 so that the refractor will swing down in the opposite direction. Of course, if it is desired to remove the refractor 7, this can be done by moving the refractor to disengage the flange 45 from the groove 19.

Referring now to the refractor 7 in detail, it is as aforesaid, preferably injection molded of crystal acrylic plastic of say about $\frac{1}{8}$ " thickness. The internal longitudinal ribs 10 or prisms 47 along the opposite sides 8 are about .06" depth. Similarly, the cones 10 arranged in crisscross rows on the bottom 9 of the refractor 7 are of about .06" altitude and have apex angles of about 104° . In practice, the die for molding the refractor 7 is made to form the bottom surface of the refractor as by employing the point of a drill having a 104° point angle and of diameter at least about $1\frac{1}{4}$ of an inch but the rows are spaced apart both longitudinally and crosswise only .153" thus to form crisscross rows of cones which, when viewed from the bottom upwardly, appear as having square bases as most clearly shown in FIG. 7.

With respect to the prisms 47 on the inside, these are of generally sawtooth form with an included angle 48 of about 70° with one side 49 at an angle of about 30° from the respective sides 8. In turn, the sides 8 are sloped downwardly and outwardly at an angle of about 25° from vertical and the bottom 9 slopes downwardly and inwardly from each side toward the center at an angle of about 5° . The prisms 47, or ribs, at the rounded lower corners of the refractor 7 are of about 55° included angle 50 for the first one, and of about 45° included angle for the second and third ones, the first one being of about $\frac{3}{32}$ " depth, the second one of about $\frac{1}{8}$ " depth, and the third one of about $\frac{5}{32}$ " depth as measured generally horizontally in FIG. 8.

Thus, it can be seen from FIG. 8 that by providing the internal longitudinal prisms 47 along the downwardly and outwardly diverging sides 8 of the refractor 7 and by providing the bottom formation of crisscross rows of cones 10, the principal light rays from each lamp 6 will be reflected and refracted as indicated by the numerous lines and arrows. Specifically, with a luminaire 1 of the type herein disclosed having the refractor 7 herein, the average brightness curves 55 and 56 of FIG. 10, crosswise and lengthwise respectively, at from 45° to 90° from nadir indicate an average brightness crosswise (curve 55) which is a minimum of about 400 footlamberts at about 65° from nadir, and an average brightness lengthwise (curve 56) which is of generally similar characteristics to crosswise brightness from about 45° to about 75° (except about 100 footlamberts less) but then from 75° to 90° the brightness lengthwise drops sharply to less than 100 footlamberts. The maximum brightness crosswise as designated by the symbols "O" from 55° to 90° is substantially uniform (about 800 footlamberts) and at 45° is about 1300 footlamberts, and the maximum brightness lengthwise as designated by the symbols "X" varies from about 900 footlamberts at 45° to about 300-400 footlamberts at 65° , 75° , and 85° , and thence drops to about 250 footlamberts at 90° . At 0° at the centerline of the luminaire the brightness is 660 footlamberts and at 0° directly beneath the lamps 6, the brightness is 2,020 footlamberts.

Now, insofar as the light distribution curves 57 (perpendicular) and 58 (parallel) are concerned as shown in FIG. 9 about 24.0% of the light output is upward, and 44.5% of the light output is downward. In the zone from 0 to 40° , the light output is 22.5% and in the zone from 0° to 60° , the light output is 35.0%.

In contrast, in a comparable fixture having vertical parallel sides on the clear plastic refractor thereof and opaque end caps coextensive with the end faces of the refractor have average crosswise brightnesses which greatly increase from 60 to 90° from nadir from about 800 footlamberts to about 1500 footlamberts and average lengthwise brightnesses which decrease from about 900

footlamberts at 45° to about 300 footlamberts at 80°. Moreover, in such luminaire, only 9% of the light output is upward, whereas 55.5% of the light output is downward.

The foregoing test results on the present luminaire 1 are based on a white enameled metal housing assembly 2 having a reflectance of about 0.90 and on two 20 watt fluorescent lamps 6 with a light output of 1380 lumens and identified as 24" T12 Standard Warm White Fluorescent Lamps. Candlepower distribution was taken in three vertical planes intersecting in the plane of the face of the refractor 7 and the test distance was 25 feet. Following is a chart plotting mid-zone candlepower at different horizontal angles in relation to mid-zone angles:

Angle, Mid-zone, degrees	Mid-Zone Candlepower— Horizontal Angles			
	Parallel	45°	Perpen- dicular	Lumens
180	49.2	49.2	49.2	-----
175	49.2	49.7	50.8	5
165	49.2	54.1	65.6	16
155	49.2	71.6	95.7	33
145	47.6	98.4	146	61
135	43.2	134	183	96
125	41.0	154	207	125
115	32.8	149	202	132
105	19.1	120	191	120
95	10.9	69.4	128	76
90	11.8	67.2	112	-----
85	20.8	71.1	111	75
75	51.9	85.8	122	92
65	74.9	104	138	104
55	121	145	182	133
45	227	266	297	204
35	357	377	391	236
25	430	443	450	205
15	470	476	480	135
5	490	491	490	47
0	492	492	492	-----

Generally, the luminaire 1 will be of 48" length using 40 watt, 2760 lumens, 48" T12 fluorescent lamps but when the length of the luminaire 60 is to be a multiple of the length of the refractor 7, it is preferred to use a continuous body member 61 as shown in FIG. 5, and to provide a single thin end plate 62 between the refractors 7 which has an ear 63 secured to the body member 61 as by means of the screw 64, but otherwise the lamp holder supports 5 and lamp holders 4, as well as the leaf springs 35 etc., are of the same structure as described in relation to the single length luminaire 1 and thus the same reference numerals have been used to denote the same parts to avoid necessity of repeating the description of the structure and operation of the FIG. 5 embodiment.

Other modes of applying the principle of the invention may be employed, change being made as regards the details described, provided the features stated in any of the following claims, or the equivalent of such, be employed.

We therefore particularly point out and distinctly claim as our invention:

1. A luminaire comprising an elongated body member having downturned outturned flanges along its opposite edges and downturned plates at its ends; lampholders secured to said luminaire between said plates for receiving a tubular lamp therebetween; a light transmitting refractor having inturned flanges along its opposite upper edges straddling said downturned flanges and resting on the respective outturned flanges and opposite sides and a bottom enclosing such lamp; said body member being formed with upwardly opening longitudinal grooves inwardly adjacent the respective downturned flanges to receive the corresponding inturned flange upon lifting and lateral shifting of that side of said refractor over the corresponding downturned flange for disengagement of the other inturned flange from the other outturned flange for downward swinging of said refractor to provide access to said body member and to such lamp and lampholders. 70

2. The luminaire of claim 1 wherein the central portion of said body member inwardly of said upwardly opening longitudinal grooves is formed as a downwardly open longitudinally extending channel in which a ballast 5 for such lamp is mounted and in which the ballast leads and lamp wiring are disposed; and wherein a cover member is detachably fitted in such channel to conceal said ballast, leads, and wiring, said cover member and body having substantially coplanar inclined surfaces to reflect light emanating from such tubular lamp. 10

3. The luminaire of claim 1 wherein the opposite sides of said refractor are formed with internal longitudinally extending ribs that constitute prisms to refract light emanating from such lamp in an angularly upward direction; and wherein the bottom of said refractor is formed with crisscross rows of cones effective to substantially reduce lengthwise and crosswise brightness of the luminaire when viewed upwardly at angles greater than about 45° from nadir. 15

4. The luminaire of claim 1 wherein said refractor has light transmitting ends disposed between said downturned plates and extending inwardly from the sides and upwardly from the bottom to the sides and bottoms of the perimeters of the respective plates; and wherein spring means 20 on said plates yieldably bear down on such upwardly extending end portions to yieldably hold said inturned flanges against said outturned flanges. 25

5. The luminaire of claim 1 wherein the opposite sides of said refractor diverge downwardly and outwardly and are formed with internal longitudinal ribs that constitute prisms to refract light emanating from such lamp angularly upward. 30

6. A luminaire comprising an elongated sheet-metal body member having a central, longitudinally extending, and downwardly open channel of which the upper edges converge downwardly; complemental converging luminaire support clamps longitudinally adjustably clamping said converging upper edges of said channel; an upwardly open channel-shaped cover member having a detachable snap connection within the upwardly diverging upper edges of the channel of said body member to form a wireway; lampholders secured to said body member adjacent the ends of the latter for receiving a tubular lamp therebetween and operatively connected to electric wiring in such wireway; and a light transmitting refractor supported by said body member, said refractor having opposite sides and a bottom enclosing such lamp. 40

7. A luminaire comprising an elongated body member having downturned and outturned flanges along its opposite edges and downturned plates at its ends; pairs of lampholders secured to said luminaire between said plates for receiving a pair of parallel tubular lamps therebetween; said body member being formed with a central downwardly open longitudinal channel inwardly of said downturned and outturned flanges; a cover member having detachable engagement with said channel to form a ballast chamber and a wireway; said body member and cover member defining a longitudinal V-shaped reflector between such lamps; a light transmitting refractor having inturned flanges straddling said downturned flanges and resting on the respective outturned flanges and opposite sides and a bottom enclosing such lamps, said refractor having light transmitting ends disposed between said plates and extending inwardly from the sides and upwardly from the bottom to the sides and bottoms of the perimeters of the respective plates; and spring means on said plates yieldably bearing down on such upwardly extending end portions to yieldably hold said inturned flanges against said outturned flanges. 50
